(57) **CLAIM**

The ornamental design for a trocar for use with morcellator, as shown and described.

DESCRIPTION

FIG. 1 is a front perspective view of a trocar for use with morcellator in accordance with the new design;

FIG. 2 is a right side perspective view thereof;

FIG. 3 is a left side perspective view thereof;

FIG. 4 is a bottom perspective view thereof; and,

FIG. 5 is a front perspective view thereof.

The broken line showing is for illustrative purposes only and forms no part of the claimed design.
